UNITED STATES PATENT OFFICE

2,005,717

BOOK STRUCTURE AND BINDER FOR
LEAVES

Melvin H. Coulston, Washington, D. C.

Application May 20, 1930, Serial No. 454,132

5 Claims. (Cl. 129—19)

An object of this invention is to provide a simple means of binding leaves which means initially can be easily and cheaply produced and which, when in use, will simultaneously expose 5 to view two or more pages of the leaves bound. A further object of the invention is to employ with such a binding means a ready means for attaching additional leaves at any time or withdrawing any previously attached leaf or leaves 10 therefrom as desired. A still further object of the invention is to produce a book structure comprising groups of leaves and binding means therefor arranged in a novel way, affording easy assemblage, disassemblage and advantageous, simultaneous exposures of leaves to view.

In the accompanying drawing which illustrates embodiments of my invention, Fig. 1 is a perspective view of a generally rectangular shaped binder means formed of flexible material. Fig. 2 shows two groups of leaves attached, respectively, to flanges or marginal hinges formed integrally with the body of the binder means of Fig. 1. Fig. 3 shows two groups of leaves attached, respectively, to hinges of a binder means 25 and two other groups of leaves attached directly to the body or unflanged portion of the binder means, respectively, adjacent to a different one of its flanges. Fig. 4 shows a perspective view of the modified form of binder used in attaching 30 more than two groups of leaves as illustrated by Fig. 3. Fig. 5 shows a modification in which a hinge or flange structure of special shape is formed separately from and suitably attached to the body of the binder means.

In all figures the same reference letters have 35 been applied to corresponding parts.

The letter A refers to the binder body which opens and closes with reference to the leaves attached to it like the covers of a book. It is preferably formed of a sheet of tough paper, flexible 40 throughout.

D and E are flanges preferably formed integrally with the body of the binder by folding over and desirably creasing marginal portions 45 thereof. As illustrated, the flange D extends along substantially the full length of a side margin of the body of the binder. The flange E extends inwardly from the opposite side margin of the binder body along approximately half of the 50 width of an end margin thereof. The inner extremity of the flange E is adjacent a line or region along which the side portions of the binder body fold or hinge with reference to each other. Small openings, suitable for the reception of attaching 55 means for leaves, are preferably formed as shown, conveniently located in the flanges D and E of the binder means. In the modified form of Fig. 3, additional, similar openings for a like purpose are shown formed in the main body portion of the 60 binder adjacent the openings in the flanges.

As shown in Figs. 2 and 3, leaves, indicated generally by the letter B, are arranged in a group and attached by suitable means, such as paper fasteners F of ordinary form, to the flange D, along one side of the binder body A, and other leaves, indicated generally by the letter C, are arranged in another group and attached by similar means to the flange E along an end marginal portion of the binder body. Thus arranged, the groups of leaves B and C, or both of them, can 10 be turned inwardly into contact with or outwardly from a juxtaposed body portion of the binder, and when both groups are so turned inwardly, they, together with the underlying portions of the binder, may be folded along a line adjacent 15 the juxtaposed edges of the groups of leaves.

Fig. 3 illustrates the modification in which the binder means is of the form shown by Fig. 4, and one or more groups of leaves, b, c, are attached directly to the body of the binder, in addition to groups of leaves B and C, attached to flanges D and E, as shown by Fig. 2. Fig. 3 illustrates the group of leaves b, attached by fasteners F directly to the binder body, closely adjacent to the flange D, extending along the length of a longitudinal, marginal portion of the binder and the group of leaves c, attached by similar means directly to the binder body, closely adjacent to the flange E, extending along a portion of the width of a marginal end portion of the binder body. The arrangement of Fig. 3 is such that the respective groups of leaves B and C, attached to flanges D and E, may be folded inwardly upon the respective groups of leaves b and c, attached to the binder body, and that thereafter the right and left portions of the binder means may be folded toward each other, carrying with them both sets of leaves, such binder portions then functioning as covers for all the groups of leaves.

It will be observed that, when the leaf groups and binder means of the structures of either Figs. 2 or 3 are folded together in the form of a closed book, a flange attached margin of one group of leaves lies immediately adjacent an unattached edge margin of another group of leaves. 45 This arrangement lends stability to the structure, and enables it to withstand harder usage.

The leaves of group C fold upwardly as they are read. This enables the reader to have immediately before him, and in substantial transverse alignment, one of the leaves of group C and either one or two of the leaves of group B. This is often a great convenience as, for example, when the matter transcribed on the leaves of group C calls for a comparison with the matter to be found upon the leaves of group B, or vice versa. Similar advantages are obviously attainable in using the groups of leaves b and c of the modified form of Fig. 3, in reference to each 55 60

other or conjointly with the groups of leaves B and C thereof.

The arrangement of Fig. 3 involves making the attaching flanges or hinges, D and E, of the binder body somewhat wider than they are in Fig. 2, so that they may respectively extend over and sufficiently beyond the edges of the respective groups of leaves, b and c, attached directly to the binder body to afford adequate anchorage for the other groups of leaves, B and C, attached to said flanges and to enable said flanges to fold over the adjacent edges of the groups of leaves b and c in a manner to bring the groups of leaves B and C into superposed relations, respectively, with the leaves of groups b and c. The arrangement of Fig. 3 will be found advantageous when the groups of leaves are very thick and their manipulation or reading is rendered difficult for that reason. It will also be found a useful means of segregating leaves of either or both groups that may carry different classes of matter.

Fig. 5 illustrates certain modified, alternative features of general mechanical equivalence to corresponding features already described and having advantages characteristic of their specific structures. Fig. 5 shows only a portion of a complete binder structure but it will be obvious therefrom how the features revealed, or any of them, can be utilized elsewhere. The attaching flange D for the group of leaves B shown, is, in this case, formed separately from the binder body portion A and is suitably secured thereto. That flange is also formed of a wider strip of material than any corresponding flange of the other figures. In addition to the part thereof immediately attached to the binder body, it includes an upstanding portion, G, of suitable width, folded directly back upon itself, and from this back folded portion there extends outwardly a portion, H, affording a backing for a group of leaves. This backing portion H carries another upstanding portion, I, spaced from the back folded portion of G. There is thus formed a generally U-shaped pocket, of requisite size, for the reception of the marginal portion of a group of leaves to be attached to the flange. The fasteners in this case traverse not only the leaves of group B but also three embracing portions of the flange D. This affords a desirably strong means of attaching the leaves to the binder body, and one protecting and improving the appearance of the attached margin thereof.

As shown by Figs. 1 to 4, inclusive each binder body is of sufficient dimension, to afford material for a hinge portion of a width adequate to admit of the cover or side portions of that body being folded together over attached groups of leaves lying between and upon them. There is no necessity, ordinarily, for giving any other attention to the structure of the hinge portion of the binder body because the natural flexibility of the stock of which it is formed will automatically serve as a hinge therefor when its side portions are folded together with the attached leaves between them.

In all of the figures of the drawing I have shown the various groups of leaves secured by a well-known type of two pronged, headed paper fastener F, but any other equivalent fastening means may be employed.

While in the accompanying drawing the groups of leaves have been shown in each figure attached respectively adjacent a left-hand margin and a

portion of the upper end margin of the binder, this is to be understood merely as a preferred manner of attachment and that the groups of leaves may be secured in a like manner to other margins of the binder if desired.

The leaves of each or either group may be structurally independent of each other except for the means that attaches them to the binder, or otherwise as desired.

I have found my invention to be of especial utility in binding together copies of patents and typed reports pertaining thereto. I conceive it, however, to have equal or greater utility in other fields. For example, it will serve the needs of students who are provided with outlines of subjects in the form of leaves or pamphlets and who are required to make notes of pertinent lectures or reports of investigations. It also affords a ready aid in the preparation of indices, and it could be used to advantage in the preparation of various educational devices such as charts or maps.

Many obvious modifications, adaptations and uses not mentioned herein will occur to those skilled in the art and fall within the scope of the appended claims.

What I claim and desire to secure by Letters Patent is:

1. A loose leaf binder structure comprising, in combination a pair of longitudinally hinged cover members, a flange hinged along a longitudinal side margin of one of the cover members, remote from the cover hinge, and another flange hinged along a transverse margin of the second cover member.

2. A loose leaf binder structure comprising, in combination, an integrally formed pair of longitudinally hinged covers, a flange integrally formed with and longitudinally hinged along a side margin of one of the covers, remote from the cover hinge, and another flange integrally formed with and transversely hinged along an end margin of the second of the covers.

3. A loose leaf book structure comprising in combination, an integrally formed pair of longitudinally hinged covers, a group of leaves attached to a flange integrally formed with and longitudinally hinged along a side margin of one of the covers remote from the cover hinge, a second group of leaves attached to a flange integrally formed with and transversely hinged along an end margin of the second of the covers, and means for attaching said groups of leaves to said flanges.

4. The combination of a binder body comprising two cover members hinged together, one of said cover members having a flange secured along a longitudinal edge thereof remote from the cover hinge, the other cover member having a flange secured along an end edge thereof, and groups of leaves secured to each of said cover members, one such group of leaves being secured to a flange of each cover member and another such group secured to each cover member adjacent its flange, and means for securing said groups of leaves as specified.

5. The combination of claim 4, in which the securing means are so arranged as to detachably secure the several groups of leaves as specified.

MELVIN H. COULSTON.
